PIANO-ACTION SPRING

Martinus Sieveking, New York, N. Y.

Application July 5, 1935, Serial No. 29,994

6 Claims. (Cl. 84—239)

This invention relates to an improved action for grand pianos and more particularly to an improved compound repeating lever and jack spring and means for varying the tension in the spring.

5 This application is a continuation in part of my application Serial No. 733,729, filed July 5, 1934.

In grand piano actions of the type herein shown, it is necessary to periodically regulate the tension exerted by the repeating lever actuating 10 spring. It has been found desirable to make the repeating lever actuating spring as long as possible so as to obtain the maximum resiliency in the spring and so that a heavy gauge spring wire may be employed. The longer the repeating lever actuating spring is made, the more readily will it absorb the rebound of the hammer blow and therefore cause smoother repetition of the action.

An object of this invention is to provide a compound piano action spring having free and slidable end portions for actuating the repeating lever and the jack, a looped end portion and an intermediate portion clamped in the flange, the said spring being made of a single length of wire and the repeating lever actuating portion being 25 of extensive length and pivoted in the support.

Another object of this invention is to provide a compound piano action spring formed to provide three integrally connected sections, each section having an independent function.

30 With the above and other objects in view, the invention will be hereinafter more particularly described, and the combination and arrangement of parts will be shown in the accompanying drawing and pointed out in the claims which form part 35 of this specification.

Reference will now be had to the drawing, wherein like numerals of reference designate corresponding parts throughout the several views, in which:

40 Figure 1 is an elevation of a grand piano action embodying my invention, the parts being partly broken away.

Figure 2 is a view of the spring in inoperative position.

45 Figure 3 is a view of the spring showing a plurality of coils in the looped end portion thereof.

In the illustrated embodiment of the invention, the numeral 10 indicates a grand piano action comprising a support 11 and a top flange 12 having a pivot 13 upon which has been mounted a repeating lever 14. A jack 15 has been pivotally mounted on a pivot 25 at one end of the support 11.

50 A compound spring 16 having an upper portion 17, a lower portion 18, a loop 19, a loop extension

20 and an intermediate brace portion 21 has been mounted on a screw or pin 22 in the support 11. The upper portion 17 has a free end 23 in flexed and slidable engagement with the lower surface of the repeating lever 14. The lower portion 18 is looped at 23 and is thereby mounted in the flange 12 by means of a screw or pin 26 and the lower end of the portion 18 is in flexed engagement and in free and slidable relation with the jack 15. The intermediate portion 21 is mounted 5 in the flange 12 between the pins 22 and 26 and is curved to form an arch. A screw 24 in threaded engagement in the support 11 has been positioned in right angular relation with the arch portion of the brace 21 and serves for springing the arch and varying the tension in the loop 19 and in the repeating lever actuating portion 17 of the spring 16. The loop extension 20 adjoins the brace 21 and is in angular relation therewith. The pressure exerted by the screw 24 against the 10 arch is transmitted by the loop extension 20 to the loop 19 and finally to the upper portion 17 of the spring 16 and reacts upwardly against the repeating lever 14. I prefer to shape the brace 21 into an arch to permit extensive movement of the screw and to secure the necessary tension adjustment in the loop 19 without permanent deformation of the brace. To prevent the brace from becoming distorted when pressed 15 upwardly by the screw 24, I have provided the loop extension 20 projecting upwardly from the loop 19 so that when the arch is flexed, the said extension transmits the motion in the arch to the loop without permanent distortion of the brace. I prefer to provide two coils in the looped 20 end portion of the spring to secure greater flexibility of the spring action.

It is to be noted that the compound spring 16 is formed to provide three integrally connected 25 sections, each section having a definite function 30 to perform in the piano action.

It will thus be noted that my compound spring performs all the functions necessary for an efficient grand piano action, in that it makes possible an unusually long repeating lever actuating section, an extensive range of adjustment of the tension in the looped end without any deformation and resulting in a piano action spring having a much longer life than those heretofore in use.

It is to be noticed that the spring is mounted 35 directly on the screws or pins 22 and 26, without the use of felt bushings between the screws or pins and the spring loops.

I claim:

50 1. In a grand piano action of the character

55

described, comprising a support having a fixed flange and a pivotally mounted jack and a repeating lever, a compound spring having a looped end mounted on a screw or pin in the support and upper and lower portions having free ends, said upper portion having its free end in flexed and slid able engagement with the lower surface of the repeating lever, a lower portion mounted in the flange and having its free end in flexed and slid able engagement with the jack and an intermediate brace portion clamped in the support and in the flange, and a screw for springing said brace to vary the tension in said loop and in said repeating lever actuating portion.

15. 2. In a grand piano action of the character described, comprising a support having a fixed flange and a pivotally mounted jack and a repeating lever, a compound spring having a looped end mounted on a screw or pin in the support and upper and lower portions having free ends, said upper portion having its free end in flexed and slid able engagement with the lower surface of the repeating lever, a lower portion mounted in the flange and having its free end in flexed and slid able engagement with the jack and an intermediate brace portion clamped in the support and in the flange, and a screw for springing said brace to vary the tension in said loop and in said repeating lever actuating portion, said loop comprising two or more coils and a loop extension adjoining said brace.

3. In a grand piano action of the character described, comprising a support having a fixed flange and a pivotally mounted jack and a repeating lever, a spring made of a single length of wire and having a looped end mounted on a screw or pin in the support and upper and lower sections having free ends, said upper section having its free end in flexed and slid able engagement with the lower surface of the repeating lever, a lower section mounted in the flange and having its free end in flexed and slid able

engagement with the jack, an intermediate brace section clamped in the flange and a loop extension integrally connecting said brace and said loop.

4. In a grand piano action of the character described, comprising a support having a fixed flange and a pivotally mounted jack and a repeating lever, a spring made of a single length of wire and having a looped end mounted on a screw or pin in the support and upper and lower sections having free ends, said upper section having its free end in flexed and slid able engagement with the lower surface of the repeating lever, a lower section mounted in the flange and having its free end in flexed and slid able engagement with the jack and an intermediate brace section clamped in the flange.

5. In a grand piano action of the character described, comprising a support having a fixed flange and a pivotally mounted jack and a repeating lever, a spring made of a single length of wire and having a looped end mounted on a screw or pin in the support and upper and lower sections having free ends, said upper section having its free end in flexed and slid able engagement with the lower surface of the repeating lever and a lower section having its free end in flexed and slid able engagement with the jack.

6. In a grand piano action of the character described, comprising a support having a fixed flange and a pivotally mounted jack and a repeating lever, a spring made of a single length of wire and having a looped end mounted on a screw or pin in the support and upper and lower sections having free ends, said upper section having its free end in flexed and slid able engagement with the lower surface of the repeating lever, a lower section having its free end in flexed and slid able engagement with the jack, and means for varying the tension in said loop.

MARTINUS SIEVEKING.
